SIMILAR ARTICLE

Ernest R. Erickson, Des Moines, Iowa

Application June 19, 1947, Serial No. 139,814

Term of patent 14 years

(Cl. D58—13)

To all whom it may concern:

Be it known that I, Ernest R. Erickson, a citizen of the United States and a resident of Des Moines, in the county of Polk and State of Iowa, have invented a new, original, and ornamental Design for a Milk Bottle Case or Similar Article, of which the following is a specification, reference being had to the accompanying drawing, forming part thereof.

Figure 1 is a perspective view of a milk bottle case or similar article, showing my new design. Figure 2 is a plan view thereof, and

Figure 3 is an end elevational view thereof.

I claim:

The ornamental design for a milk bottle case or similar article, substantially as shown.

ERNEST R. ERICKSON.
